SANDPAPER DRUM

Oscar E. Hadwiger and Harry O. Schmidt,
Pueblo, Colo.

Application March 4, 1938, Serial No. 193,988

2 Claims. (Cl. 51—194)

This invention relates to sand drums, the primary object of the invention being to provide a sand drum of a construction to insure the sand cloth being firmly held in position on the drum 5 and one in which the sand cloth will be stretched over the drum, providing an even sanding surface.

A further object of the invention is to provide a drum which will cushion the sanding surface of the drum, thereby greatly increasing the life of 10 the sand cloth. A still further object of the invention is to provide a sand drum wherein the sand cloth may be readily positioned, the clamping of the sand cloth being incident to the securing of the drum sections together.

15 Referring to the drawing in detail,

Figure 1 is an elevational view of a sand drum constructed in accordance with the invention.

Figure 2 is a longitudinal sectional view through the sand drum.

20 Figure 3 is a transverse sectional view taken on line 3—3 of Figure 2.

Figure 4 is a transverse sectional view taken on line 4—4 of Figure 2.

25 Referring to the drawing in detail, the sand drum comprises a body portion including semi-cylindrical sections 5 and 6, each section being provided with end members 7, which are formed with openings to receive the supporting shaft 8 which is secured in position, by means of bolts 9 extending through the section 5, and disposed 30 near the ends thereof, and the screw 10 disposed substantially intermediate the ends of the section 5.

The sections 5 and 6 are hingedly connected, as 35 at 11, so that the sections may be pivoted with respect to each other, and swung open, to facilitate the positioning of the sand paper, indicated by the reference character 12.

An opening is formed substantially intermediate 40 the ends of the section 6, and is designed to accommodate the screw 13, which has its threaded end fitted in the threaded opening 14, disposed intermediate the end of the supporting shaft 8. Thus it will be seen that due to this construction, 45 the sections may be moved together, and held in such position, by means of the screw 13.

As clearly shown by Figure 3 of the drawing, the sections of the body portion carry a plurality of pins 15, which are adapted to extend into 50 recesses or openings formed in the opposite section, and disposed directly opposite to the pins when the sections are moved to their closed positions.

The outer surface of the drum is covered by a 55 layer of sponge rubber indicated by the reference

character 16, the ends of the layer of sponge rubber 16 terminating at points adjacent to the free edges of the semi-cylindrical sections 5 and 6.

As shown, the sand paper 12 is stretched over the layer of sponge rubber 16, the ends of the sand paper being pressed over the pins 15, securing the ends of the sand paper in position.

It will be seen that when the sections 5 and 6 are moved to their open positions, or to positions where the free edges thereof lie in spaced relation 10 with respect to each other, the layer of sponge rubber becomes compressed, at points adjacent to the pivots of the sections 5 and 6, to the end that the sand paper may be readily stretched there-over with little exertion and trouble on the part 15 of the person positioning the sand paper.

When the sections 5 and 6 are moved to their closed positions, and secured in such position by means of the securing screw 13, the inwardly turned ends of the sand paper 12 will be clamped 20 between the adjacent edges of the sections 5 and 6, securely holding the sand paper in position.

A counterbalancing weight indicated by the reference character 17 is secured within the section 5, at a point adjacent to the inwardly extended 25 ends of the sand paper.

From the foregoing it will be seen that due to the construction shown and described, we have provided a sand drum which will permit the sand paper to be readily and easily positioned, and at 30 the same time will insure a regular surface for contact with the surface being sanded.

It might be further stated that the free edges of the sections 5 and 6 are cut at oblique angles with respect to the ends thereof, with the result that 35 the sand drum will operate with less chance of the cloth buckling or creeping, and at the same time insure a smooth surface being formed by the sand drum.

Having thus described the invention, what is 40 claimed is:

1. A sand drum comprising a pair of pivotally connected semi-cylindrical sections, pins extending from one of the sections, a strip of sanding cloth having openings at its ends through which 45 the pins extend, the ends of the sanding cloth being clamped between the free edges of the semi-cylindrical section, a shaft extending through the drum and having threaded openings formed therein, screws extending through the cylinder, 50 the inner ends of the screws extending into the threaded openings of the shaft, and said screws adapted to draw the sections of the drum together tensioning the sand cloth.

2. A sand drum comprising a pair of pivotally 55

connected semi-cylindrical sections, a cushioning member on the drum, a shaft on which the drum is mounted, screws extending through one of the sections of the drum near the ends thereof for securing one of said sections to the shaft, screws extending through both sections and extending into the shaft securing the drum to the shaft, a

length of sand cloth positioned on the drum, the ends of the sand cloth being clamped between the ends of the sections of the drum, and the latter screws adapted to tension the sand cloth.

OSCAR E. HADWIGER.
